VALVE HOUSING

Frank K. Villari, Oak Park, Ill., assignor to
The Kendall Company, Walpole, Mass.

Filed July 8, 1974, Ser. No. 486,511

Term of patent 14 years

Int. Cl. D23—01

U.S. Cl. D23—19

FIG. 1

FIG. 2

FIG. 3

FIG. 4

FIG. 5

FIG. 6

FIG. 1 is a perspective view of a valve housing embodying my new design;

FIG. 2 is a side elevational view thereof;

FIG. 3 is an elevational view taken from one end thereof;

FIG. 4 is a top plan view thereof;

FIG. 5 is an elevational view taken from the end opposite that shown in FIG. 3; and

FIG. 6 is a bottom plan view thereof.

I claim:

The ornamental design for a valve housing, substantially as shown.
